UNITED STATES PATENT OFFICE.

CHARLES J. LUCE, OF NIANTIC, CONNECTICUT, ASSIGNOR, BY MESNE ASSIGNMENTS,
TO STANDARD COMPRESS AND WAREHOUSE CORPORATION, A CORPORATION OF
VIRGINIA.

COTTON-COMPRESS.

1,261,043.

Specification of Letters Patent.

Patented Apr. 2, 1918.

Application filed June 20, 1913, Serial No. 774,802. Renewed September 22, 1916. Serial No. 121,685.

To all whom it may concern:

Be it known that I, CHARLES J. LUCE, a citizen of the United States, residing at Niantic, in the county of New London and State of Connecticut, have invented certain new and useful Improvements in Cotton-Compresses, of which the following is a specification.

This invention relates broadly to cotton compressors, and more particularly is designed to provide compressing apparatus adapted for a secondary or other subsequent and more compact and accurate compression of a preliminarily and usually roughly and approximately pressed bale. The particular structure in which the invention is embodied includes a set of end compressor members whereby the bale is endwisely compressed, a set of side compressor members whereby the bale is next sidewise compressed, and upper and lower compressor members or platens between which the bale is given a vertical compression.

One of the objects of this invention is to provide an apparatus of the above character, preferably controlled and actuated by hydraulic or other fluid means adapted for simple and accurate operation.

Another object of the invention is to provide in this connection a type of hydraulic or equivalent means so arranged and constructed that automatic actuation of the plurality of compressor members controlled thereby may predeterminedly take place in proper sequence.

A further object of the invention is to provide a set of members for endwisely compressing a bale, and a set of members for sidewise compressing the bale, together with a common means for actuating such sets of compressor members in desired sequence.

Still another object is to provide lever or equivalent connections for certain of the last named compressor members, under control of the hydraulic actuating means, whereby the effective leverage upon such compressor members increases in accordance with the advance of compression; whereby when the compression induced by said compressor members is at its desired maximum the compressor members will be held in locked condition, without requiring any additional or special locking means; and whereby, in con-

nection with the hydraulic means employed, 55 the compression of certain of the compressor members may be gradually eased down and released, without shock and without tendency to distortion of the bale.

Another object of the invention is to 60 provide, in connection with the hydraulic or equivalent compressor-member operating means, attachments and arrangements whereby the comparatively slight endwise and sidewise compression and the initial 65 vertical compression takes place rapidly, whereby the succeeding vertical or final compression takes place more slowly, but with proportionate increase of power.

Other objects and aims of the invention, 70 more or less broad than those stated above, together with the advantages inherent, will be in part obvious and in part specifically referred to in the course of the following description of the elements, combinations, arrangements of parts, and applications of principles constituting the invention; and the scope of protection contemplated will appear from the claims.

In the accompanying drawings, which are 80 to be taken as a part of this specification, and in which I have shown one of the various possible embodiments of this invention as at present preferred:

Figure 1 is a front elevation of said embodiment, illustrating the compressing instrumentalities in locked position;

Fig. 2 is a top plan view of said embodiment and with the arrow 20 pointing toward the front of the apparatus, but with the 90 parts located above the line 2—2 of Fig. 1 not disclosed;

Fig. 3 is a vertical sectional view taken on the line 3—3 of Fig. 1 and looking in the direction of the adjacent arrows, certain of 95 the parts being broken away and certain of the parts being shown in section;

Fig. 4 is a view similar to Fig. 1, but with certain of the parts broken away, and showing the end doors in open position;

Fig. 5 is a detail view, illustrating certain of the parts shown in Fig. 3, and looking in the direction of the arrow 5' of Fig. 1;

Fig. 6 is a top plan view of the parts shown in Fig. 5;

Fig. 7 is a side elevation of the parts shown in Fig. 5 and looking in the direction of the arrow 21;

Fig. 8 is a view similar to Fig. 5, but looking in the direction of the arrow 5 on Fig. 1, and showing the parts in open position;

Fig. 9 is a view similar to Fig. 6, but 5 showing the parts in open position;

Fig. 10 is a detail side elevation of one end of the press;

Fig. 11 is a detail view in top plan of one 10 of the toggle mechanisms hereinafter described located on the left-hand side of Fig. 2 and with the side doors 22 locked in position;

Fig. 12 is a front elevation of the parts shown in Fig. 11;

15 Fig. 13 is a detail view in top plan of one of said toggle mechanisms located on the right-hand side of Fig. 2 and with the side doors 22 in locked position;

Fig. 14 is a front elevation of the parts 20 shown in Fig. 13;

Fig. 15 is a detail view in top plan of one of said toggle mechanisms located on the left-hand side of Fig. 2 and with the side doors 22 in open position;

25 Fig. 16 is a front elevation of the parts shown in Fig. 15;

Fig. 17 is a detail view in top plan of one of said toggle mechanisms located on the right-hand side of Fig. 2 and with the side 30 doors 22 in open position;

Fig. 18 is a front elevation of the parts shown in Fig. 17;

35 Fig. 19 is a diagrammatic lay out of a hydraulic means or the like which may with advantage be utilized in connection with this embodiment of this invention;

Fig. 20 is a detail showing the connections between the side and end compressing plates and the ram which actuates them; and

40 Fig. 21 is a section on the line 21—21 of Fig. 20.

Similar reference characters refer to similar parts throughout the several views of the drawings.

45 Referring now to the accompanying drawings, the reference numeral 23 represents a foundation for supporting the apparatus and carries centrally thereof a tri-bore cylinder 24, within each of the bores of which 50 is adapted to be accommodated, as best shown in Figs. 1 and 4, a ram 25 preferably as shown, which rams at their upper termini are attached to, support, and control the elevation of, a lower movable platen 26. The 55 platen being oblong, the provision of the plurality of rams disposed side by side insures positively guided vertical movement of the platen, in spite of any possible variations in density between different parts of

60 the bale. Mounted within and extending upwardly from foundation 23 are a plurality of supporting standards 27, carrying at their upper ends a roof-member 28 as shown. Fixedly attached to the underside 65 of said roof-member, and preferably in ver-

tical alinement with the horizontally movable platen 26 is a fixed upper platen 29. Platens 26 and 29 are provided as shown with a plurality of band or strap grooves 30 (Figs. 1 and 4), and each of the grooves 30 70 carried by upper platen 29 is in vertical alinement with one of the lower grooves 30 carried by the lower platen 26, each of said grooves being preferably in cross-section inwardly flaring or of a dovetail character as 75 shown. The cylinder bores within the cylinder 24 are illustrated in Fig. 19 as at 24', in association with certain of the piping or the like arrangements for the hydraulic or equivalent system which will be hereinafter 80 described. Also disclosed in Fig. 19 are a plurality of pressure cylinders 31 in like association, which cylinders 31 are also disclosed in Fig. 1 and in certain of the other figures. The bore of each cylinder 31 accom- 85 modates a ram 32, which rams control the endwise and sidewise compression, as well as the subsequent locking of the endwise and sidewise compressing instrumentalities and also the unlocking of the same. 90

In Fig. 3 there is disclosed in connection with this embodiment of my invention, a supporting frame-work 33 for the cylinder 24, a similar suspending frame-work for the upper platen 29, and a floor 35. In this Fig. 95 3 is shown also the ram 25, its supported platen 26, and a bale of cotton or the like 36 in course of compression.

A top plan view of the apparatus before the insertion therein of a mass of material 100 to be compressed would be substantially similar to Fig. 2. As shown in that figure, there are sidewise compressor members or doors 22, hinged to rods 27' by means of a plurality of collars 37 (see also Fig. 8, which 105 is a view looking in the direction of the arrow 20 of Fig. 2, but not Fig. 5, which is a view looking in the direction of the arrow 42' of Fig. 2). These side doors 22 are shown extended in said Fig. 2, and with the 110 collars 37 engaging by means of set screws as illustrated the rods 27'. Adverting now to Figs. 8, 9 and 10, it should be understood at this point that when a bale is to be compressed the side doors 22 are preferably 115 manually or otherwise swung in to take up the dotted line positions 22' illustrated in Fig. 2 (but not to take up the dotted-and-dashed line positions 22'' illustrated in said Fig. 2, which latter location is brought about 120 as hereinafter described during the subsequent operation of the apparatus). Two sets of end links 38, each set comprising a vertical row of links, each link of which is pivotally mounted upon one of the sliding 125 pieces 39 or 40 (Figs. 8, 9 and 10, and 11 to 18 inclusive), and through each of which sets passes a rigidly-secured locking rod 41, having been swung around to the locations indicated at 38' in Fig. 2, the locking rods 130

41 engage in the manner described below with the keepers 42 carried by the side doors 22 upon their outer faces. From Fig. 1 it will be observed that each of these side doors 22 is composed of a plurality of horizontal I-beams 22, each of said I-beams being rotatively mounted upon a non-rotative vertical hinge rod 27', and supported against vertical downward travel on said rod as by means 5 of the collars 37, secured on the rods 27' by the set screws 27'', and that said horizontal means are spaced apart and rigidly connected by means of the vertically extending cross I-beams 43. Each of these side doors 10 carries thereon a presser-plate 49 supported by the I-beams 43 as shown in Fig. 2. Each hinge rod 27' is supported at its lower end by means of a rigidly connected tracker-member 51 which rides upon a track 52 (Fig. 1) and the upper end of the rod moves 15 within a slot 53 formed in one of the slot-plates 54 carried as shown in Figs. 1, 2 and 3, upon roof-member 28, a correspondingly slotted casting 54' overlying the plates 54 above the slot 53 to protect the end of the rod. With the side doors 22 preparatory 20 swung inwardly to take up the location shown at 22' in Fig. 2 as aforesaid, the hinge rods 27' rest in said slots 53 (and correspondingly on said tracks 52) as disclosed 25 in Fig. 2, that is, parallelly spaced away to the maximum from the longitudinal center-line 55—55 shown in Fig. 2.

It will be observed from Figs. 1 and 2, and 30 from certain portions of Figs. 1 and 2 viewed in the direction of the arrow 5 shown in said Fig. 1 and in the direction of the arrow 20 shown in said Fig. 2, that a plurality of sets of sliding bars 44 and 45 extend horizontally transversely of the apparatus, the apertured terminus of each of said bars collaring as shown at 45' in Fig. 8 one of the hinge rods 27' upon which the side doors 22 are mounted as aforesaid. 35 These bars 44 and 45 slide upon one another, as most clearly shown in the detail disclosures of Figs. 17 and 18, and are adapted when horizontally overlapping each other to a lesser extent, as in said Figs. 17 and 18, to 40 maintain the hinge rods 27' of doors 22 parallelly spaced away to the maximum from the longitudinal center-line 55—55 shown in Fig. 2; and, as most clearly shown in Figs. 13 and 14, are adapted when horizontally overlapping each other to a greater 45 extent, to draw the hinge rods 27' of side doors 22 inwardly toward said center-line 55—55; that is, to draw the rods 27' to the other extremity of each slot 53 from the extremity illustrated in Fig. 2, and simultaneously to cause the tracker member 51 to travel away from the observer upon the track 52 shown in Fig. 1. The relative sliding movement of bars 44 and 45, to draw 50 the hinge rods 27' toward each other or to

move them away from each other is brought about by means of links 56 and 57, the link 56 in each case being connected to the bar 45 by means of a pivotal connection 58 to a depending U-lug 59 at the inner end of bar 45, and the link 57 in each case being connected by a similar pivotal connection 60 to a U-lug 61 at the inner end of bar 44. The bar 44 slides between the legs of the U-lug 59 above the pivot 58 and the bar 45 70 slides above the pivot 60 and between the pivot 60 and a pin 62 that extends between upwardly extending side pieces 63 that are continuous with the legs of the U-lug 61. There are two sets of these links 56 and 57, 75 connected to the sliding members 44 and 45 as described, and the other ends of these sets of links 56 and 57 are secured to vertically reciprocating bars 64, one on each side of the sliding members 44 and 45, as appears 80 in Figs. 1, 13 and 17. The sliding members 44 and 45 are supported against vertical displacement as by means of the castings 44' which are secured to the supporting rods 27 and which provide vertically spaced pairs of 85 horizontally spaced fingers 46', so that the sliding members 44 and 45 may be supported between fingers 46', and so that the two reciprocating bars 64 find a way in the space between the two pairs of fingers 46' (see 90 Figs. 8, 9 and 10). The extreme positions of this reciprocating bar 64 are shown in Figs. 14 and 18 respectively, Fig. 14 showing the bar 64 in its uppermost position, with the sliding members 44 and 45 overlapping each other so as to draw the hinge rods 27' toward each other, and Fig. 18 showing the lowermost position of the reciprocating bars 64, with the sliding members 44 and 45 moved to the position in 100 which the hinge rods 27' are moved away from each other. The operating means for the hinge rods are thus in effect a series of identically and simultaneously acting toggles, and when the links 56 and 57 have 105 reached the position of Fig. 14, that is, when they are straightened out, it will be apparent that the hinge rods 27' will be locked in position as close together as they can be brought, and that they cannot be moved 110 from this position except upon the positive application of power to move the reciprocating bars 64 downwardly. Furthermore, by the employment of these cross-over toggles, the leverage increases as the hinge rods 115 are brought closer together, this increase corresponding with the advancing sidewise compression and consequent increasing resistance.

The locking rods 41 carried by the various 120 links 38, which as above suggested are provided to engage with the keepers or retainers 42 carried by the side doors 22 when the side doors are brought to the position indicated at 22' in Fig. 2, are intended to be drawn 130

together and forced apart in the same manner as and concurrently with the relative movements of the hinge rods 27'. To that end the links 38 are pivotally connected to 5 sliding pieces 39 and 40, as shown in Figs. 11, 12, 15 and 16, which sliding pieces 39 and 40 correspond to the sliding members 44 and 45, and are connected by means of links 65 and 66, corresponding to the links 10 56 and 57 previously described, to reciprocating bars 67 corresponding to the reciprocating bars 64 previously described in connection with the actuation of the hinge rods 27'. The locking rods 41 are thus actuated 15 in substantially the same manner as and simultaneously with the hinge rods 27', so that, assuming the parts to be in the position shown at 22' in Fig. 2, if the bars 64 and 67 are simultaneously moved from the position 20 which they respectively occupy in Figs. 18 and 16 to the positions which they respectively occupy in Figs. 14 and 12, the side doors or compressor members 22 will be brought from the position indicated at 22' 25 to the position indicated at 22'' in Fig. 2, and upon a reverse movement of the reciprocating bars 64 and 67, the side doors 22 will be brought from the position indicated at 22'' to the position indicated at 22'. The 30 drawing of the side doors together will of course compress a bale sidewise, and the separation of the side members 22 will release the sidewise compression.

For the endwise compression of the bale, 35 and coöperative with the sidewise compressors 22, I provide end doors 68, each of which is carried by a support 69 that is pivoted to the frame-work as indicated at 70. The open position of these end doors 68 is 40 shown in Fig. 4, and the closed position thereof is shown in Fig. 1, for instance. Each of these end doors 68 carries on its outer face a pair of projections 71 having an inclined face 72 and a face 74 that is 45 parallel to the face of the door 68. Coöperating with the surfaces 72 and 74 of the projections 71 are rollers 75 mounted on a shaft 76, and this shaft 76 also carries a pair of rollers 77 that coöperate with the surfaces 50 of projections 78 upon castings 79 that are secured upon supporting rods 27. It will be evident that if the shaft 76 is moved from the position shown in Fig. 10, for instance, to the position shown in Fig. 7, the door will 55 be brought to a vertical position. This movement of the shafts 76 is brought about by means of the hydraulic rams 31, the heads 80 of which are connected to the shaft 76 by means of parallel links 81, so that as the 60 head of the ram rises from the position shown in Fig. 10, for instance, to the position shown in Fig. 7, the rollers 75 and 77 will be forced between the opposing surfaces of the projections 71 on the end doors and 65 the opposed projections 78 on the castings

79. While the rollers 75 are traversing the inclined surface 72 of the projections 71 the door is gradually straightened up to a vertical position, and when the rollers 75 reach the surfaces 74 their further upward vertical travel causes no further movement of the doors 68. The rams 31, besides causing the actuation of the end doors 68, are intended also to actuate the several pairs of reciprocating bars 64 and 67, so as to operate the side compression members. This is accomplished by providing the head of each ram 31 with an upstanding part 82 carrying a pin 84 that projects on opposite sides and extends through elongated slots 85 in 80 the lower ends of the two reciprocating bars 64 or 67 as the case may be. Assuming the parts to be in the position shown in Fig. 8, if the head of the ram begins to rise, the first effect will be to carry upwardly the 85 links 81, whereby the doors 68 are brought to the vertical position. At the moment when the rollers 75 reach the surfaces 74 of the projections 71, the pins 84 have reached the lower ends respectively of the slots 85 in 90 the pairs of reciprocating bars 64 and 67, and the lower ends of said reciprocating members 64 and 67 are in contact with the head of the ram adjacent the base of the upstanding part 82, so that as the head of the 95 ram continues in its upward course, it carries the pairs of reciprocating bars 64 or 67 with it, thereby straightening out the toggles and drawing the side doors or compressor members toward each other in the manner already described. Thus it will be evident that the end doors are brought to the vertical position first, and before the side doors begin to approach each other. As these side doors approach each other, locking grooves 86 which are formed therein engage the edges of the end doors 68, thereby forming a complete box, the parts of which are securely held together. Preferably the mouths of these grooves 86 are beveled off 100 as shown, so as to guide the end doors into place and also to prevent shock when the compression is released and the side doors begin to separate from each other. If it were not for this provision, when the side 105 doors separate the end doors would suddenly snap out of the grooves 86 on account of the endwise expansion of the bale, and there would be a tendency to distortion of the bale.

Assuming that the end doors have been straightened up in the manner described, and that the side doors have thereupon been drawn together and interlocked with the end doors, so that the bale has been subjected to endwise and sidewise compression, 125 the next step is to cause vertical compression of the bale. This is brought about by upward movement of the lower movable platen 26 to the position shown in Figs. 3 and 4, by 130

the operation of the rams 25. It should be understood that there is a row of three of these rams 25 for operating the platen 26, the cylinder of the middle ram being of considerably larger cross-section than those of the two end rams. It is contemplated that in the elevation of the movable platen for vertically compressing the bale, pressure shall be admitted first to the two smaller end 5 cylinders, so that the two end rams move upwardly at a comparatively rapid rate of speed, and that when the compression has advanced to a certain predetermined stage at which the resistance of the bale becomes 10 greater, the pressure shall be admitted also to the middle and larger cylinder, after which the elevation of the platen continues more slowly but with increased power. How all this is accomplished will be best understood 15 from the description of the hydraulic apparatus and controls hereinafter described. When the bale has been endwisely and sidewisely and vertically compressed in the manner stated, the compression of the 20 side doors is first released; then the end doors move back to the position shown in Fig. 4, whereupon the side doors may be released from their locking rods 41 and swung open to the position shown in full 25 lines in Fig. 2. Meantime, the movable platen 26 is held in its elevated position shown in Fig. 4, and the securing bands 87 are passed around the bale by way of the alined dovetail grooves in the fixed and 30 movable platens. These grooves are larger at the bottom so that the bands may be readily inserted, and are contracted at their mouths so that as the bands are drawn taut they are properly guided and alined. The 35 cover for the bale will of course have been put in position before the compression is initiated, and since the bale is slightly over-compressed vertically, the ends of the cover may be tucked under the end bands, so that 40 45 when the vertical compression is released the consequent expansion of the bale will hold the cover between it and the bands.

Referring now to Fig. 19, there is shown at 88 the usual tank for the hydraulic system, and at 89 there is indicated a pump. From the pump leads a pipe 90, with an interposed pressure valve 91, which pipe 90 connects by means of the pipe 92 with the two end cylinders 24'. From the pipe 90 50 there is also a branch 94 which connects with a pipe 95 leading to the middle and larger cylinder 24', the branch pipe 94 being provided with a pressure valve 96. The pressure valves 91 and 96 are of such construction respectively that the pressure valve 91 will open upon a less pressure than the pressure valve 96, so that the fluid will be sent to the end cylinder 24' first, and will not be sent into the middle or larger cylinder 24' 55 until pressure has increased to a predetermined point. The pipe 95 is connected by a pipe 97 and a pipe 98 with the tank 88, and there is a check valve 99 in the pipe 97, so that as the two end rams 25 begin to rise, carrying with them of course the middle or 60 larger ram 25, the suction induced by the latter in the pipe 95 will cause the fluid to pass from the tank 88 through the pipes 98 and 97 past the check valve 99 into the pipe 95 and following the rising ram in the larger 65 middle cylinder 24'. Thereupon, as the pressure rises, the pressure valve 96 opens and the pressure enters the pipe 95, so that the active fluid pressure will then be operating within all three of the cylinders 24'. The 70 provision of the check valve 99 and the connection to the tank 88 insures that there will be inert fluid behind the larger central ram 25 at the moment when the active pressure is turned into the middle cylinder, so that no 75 time is lost in pumping the fluid into this middle cylinder. The pipe 95 is also connected to the tank 88 by another pipe 100, in which pipe 100 there is a globe valve 101, the purpose of which is to empty the middle 80 cylinder 24' when the pressure is released. Also communicating with the pipe 90 there is a pipe 102, which connects with a pipe 104 that opens into a union controlled by a three-way valve 105. This valve 105 controls the passage between pipe 104 and a pipe 106 that leads directly to the lower end of one of the cylinders 31, and by means of a branch 107 to the lower end of the other cylinder 31. The valve 105 also controls the 85 passage between the pipe 104 and a pipe 108 that leads into the tank 88 by way of the pipe 98. 109 indicates a union connecting the pipe 102 with the pipe 104 and with another pipe 110, and in the pipe 104, between 90 the union 109 and the three-way valve 105 there is a check valve 111, which opens toward the three-way valve 105. The pipe 110 is connected by means of a three-way valve 105 95 with a pipe 114 and with another pipe 115. The pipe 114 leads directly to the top of the cylinder 31, and by means of a branch 116 to the top of the other cylinder 31; and the pipe 115 leads to the tank 88. In operation the three-way valve 105 is turned so that 100 the fluid from the pump passes through the pipe 90, pipe 102, through check valve 111, through pipe 106 to the bottom of one cylinder 31, and through the branch 107 to the bottom of the other cylinder 31. The passage from pipe 104 to pipe 108 is closed in this position of the three-way valve 105, and at the same time the three-way valve 112 is turned so that there can be no communication between the pipe 102 by way of the 105 union 109 and the pipe 110 with the pipes 114 or 115. Upon the admission of pressure 110 in this way to the lower ends of the cylinders 31, the rams in the cylinders begin to rise, thereby first straightening up the end 115 120 125 130

doors 68, and afterward drawing together the hinge rods 27' and the locking rods 41 of the side compressor members. This being accomplished, as the pumping continues and the pressure increases, the pressure valve 91 opens and fluid is admitted through this pressure valve 91 into the piping 92, whereupon the two end rams of the three rams that control the movable platen 26 begin to rise, accomplishing the initial vertical compression of the bale. Since the ram of the middle or larger cylinder 24' for the movable platen moves forward at the same time with the movement of the end rams 24', the suction thereby induced in the middle cylinders 24' causes the water to flow from the tank 88 through the pipe 97, past the check valve 99, and through the pipe 95 and to follow closely behind the ram of the middle cylinder. As the pressure still increases, and when it reaches a predetermined point, the check valve 96 opens, whereupon active pressure is directed from the pipe 90 through pressure valve 96 and into the pipe 95 and thence into the lower end of the middle cylinder 24', so that all three of these cylinders 24' are now under pressure, and the final vertical compression of the bale is accomplished more slowly than was the initial vertical compression accomplished by the two end cylinders 24', but with greater power, corresponding to the increased resistance offered by the bale.

When the compression has been completed and it is desired to release the bale, it is first necessary to manipulate the three-way valves 105 and 112. The valve 105 is turned so that the water on the underside of the piston in the cylinders 31 may find a way through the pipes 107 and 106 through the valve 105 and the pipe 108 into the tank 88. The valve 112 is turned so that the fluid pressure induced by the pump 89 may find a way through the pipe 90 by way of the pipe 102, through the pipe 110 and through the pipes 114 and 116, into the upper ends of the cylinders 31 above the pistons thereof. In the meantime, the pressure is held in all three of the cylinders 24'. The effect of the pressure passing into the upper ends of the cylinders 31 as described is to lower the pistons thereof, whereby the release of the compression of the end doors and side door is brought about. This release is without shock, because as the fluid pressure enters the upper ends of the cylinders 31 the pistons thereof are driven downwardly and force out the fluid from the undersides of the pistons, which fluid acts as a cushion. The side and end doors being thus released, and the bale tied, the fluid pressure is discontinued by stopping the pump, whereupon the globe valve 101 is turned so that the three cylinders 24' may be vented into the

tank 88; the middle cylinder by way of the pipe 100 and the two end cylinders 24' by way of the pipe 90, through the valve 91, which for this purpose is a check valve as well as a pressure valve, through the pipe 102, through the union 109, pipe 110, valve 112, and by way of the pipe 115 to the tank 88.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

Having described this invention, what I claim as new and desire to secure by Letters Patent is:

1. In a device of the kind described, the combination of a pivotally movable compressor member, a pivotally and bodily movable compressor member, and a common fluid operated means for moving the compressor members in sequence.
2. In a device of the kind described, the combination of a pivotally movable compressor member, a pivotally and bodily movable compressor member, and means causing the compressor members to move in sequence, and causing one of the compressor members to move with positive acceleration and thereafter with negative acceleration.
3. In a device of the kind described, the combination of a pivotally movable compressor member, a bodily movable compressor member, and means for moving the compressor members, said compressor members having interengaging portions.
4. In a device of the kind described, the combination of a pivotally movable compressor member, means for moving the member to a vertical position, a bodily and pivotally movable compressor member, and means for moving the last-named compressor member, the two compressor members having portions which may interengage when the first-named pivotally movable compressor member is in a vertical position.

5. In a device of the kind described, the combination of a compressor member, a rod upon which the compressor member is pivoted, and means for moving the rod bodily in a direction transverse to its axis.

6. In a device of the kind described, in combination, a bodily movable rod upon

which the compressor member is pivoted, a second rod, a link to which the second rod is secured, an actuating member to which the link is pivoted, the second rod and the 5 compressor member having interengaging portions, and means for simultaneously moving the first-named rod and the actuating member.

7. In a device of the kind described, in 10 combination, a compressor member, a rod movable in a straight line and upon which the compressor member is pivoted, and a locking rod adapted to engage the compressor member, said locking rod being 15 movable in an arc and also in a straight line.

8. In a device of the kind described, the 20 combination of opposed compressor members bodily movable toward and from each other, each of said compressor members having a bodily shifting pivot, a locking rod for each compressor member, and means for drawing the pivots toward each other and for simultaneously drawing the locking rods 25 toward each other.

9. In a device of the kind described, the 30 combination of opposed compressor members bodily movable toward and from each other, each of said compressor members having a bodily shifting pivot, a locking rod for each compressor member, means for drawing the pivots toward each other and for simultaneously drawing the locking rods toward 35 each other, and another pair of opposed compressor members extending at right-angles to the first pair of compressor members and interengaging with the latter.

10. In a device of the kind described, the 40 combination of opposed compressor members bodily movable toward and from each other, each of said compressor members having a bodily shifting pivot, a locking rod for each compressor member, means for drawing the pivots toward each other and for simultaneously drawing the locking rods toward 45 each other, and another pair of opposed compressor members extending at right-angles to the first pair of compressor members and interengaging with the latter, 50 the second pair of compressor members being pivotally movable.

11. In a device of the kind described, the 55 combination of a pivotally mounted compressor member adapted to be brought to a vertical position, another compressor member that is bodily movable in a direction transverse to the first compressor member, a motor, connections between the motor and the pivoted compressor member whereby 60 upon operation of the motor the pivoted compressor member is brought to a vertical position, and connections between the motor and the second compressor member whereby after the first compressor member is brought

to a vertical position the second compressor 65 member is moved bodily with respect to the first compressor member, the compressor members having parts that interengage.

12. In a device of the kind described, the 70 combination of a pivoted compressor member having an outside projection that is provided with an inclined surface and with another surface that is parallel to the surface of the compressor member, a plunger, and a link pivoted to the plunger and having 75 a bearing portion for engagement with the surfaces of the projection on the compressor member.

13. In a device of the kind described, the 80 combination of a pivoted compressor member having an outside projection that is provided with an inclined surface and with another surface that is parallel to the surface of the compressor member, a plunger, a link pivoted to the plunger and having a 85 bearing portion for engaging with the surfaces of the projection on the compressor member, and means for maintaining the bearing portion of the link in engagement with the projecting part of the compressor 90 member.

14. In a device of the kind described, in 95 combination, a compressor member for one horizontal dimension of a bale, a compressor member for the other horizontal dimension of a bale, a plunger, a lost-motion connection between the plunger and the first compressor member, and a lost-motion connection between the plunger and the second compressor member, whereby upon actuation of the plunger the first compressor member 100 is moved to a predetermined position and thereafter the second compressor member is moved while the first compressor member remains in the position to which 105 it has been brought.

15. In a device of the kind described, in 110 combination, a pivoted compressor member for one of the horizontal dimensions of a bale, which compressor member is adapted to be brought to a vertical position, a bodily movable compressor member for the other horizontal dimension of the bale, a plunger, a link actuated by the plunger and bearing upon the first compressor member whereby 115 to move the latter to a vertical position, a sliding member adapted to be moved by the plunger after the latter has brought the first compressor member to the vertical position, and connections between the sliding 120 member and the second compressor member whereby upon a further actuation of the plunger the second compressor member is moved toward the first compressor member.

16. In a device of the kind described, the 125 combination of a pivoted compressor member for one of the horizontal dimensions of a bale, which compressor member is adapted

to be brought to a vertical position, an outside projection upon the compressor member having an inclined surface and having also a surface parallel to the surface of the compressor member, a plunger, a link pivoted to the plunger, and a roller at the end of the link adapted to bear upon the surfaces of said projection.

17. In a device of the kind described, the combination of a pivoted compressor member for one of the horizontal dimensions of a bale, which compressor member is adapted to be brought to a vertical position, an outside projection upon the compressor member having an inclined surface and having also a surface parallel to the surface of the compressor member, a plunger, a link pivoted to the plunger, a roller at the end of the link adapted to bear upon the surfaces 20 of said projection, and a member opposite said projection between which and the projection the roller is adapted to bear.

18. In a device of the kind described, the combination of a pair of opposed compressor members for one of the horizontal dimensions of a bale, a means for moving them toward and from each other comprising sliding members at the ends of the compressor members, and cross-over toggles connected to 25 the compressor members and to the sliding members, and plungers operatively related to the sliding members whereby the sliding members are actuated by the plungers after the plungers have moved to a predetermined extent.

19. In a device of the kind described, the combination of a pair of opposed compressor members for one of the horizontal dimensions of a bale, means for moving them toward and from each other comprising sliding members at the ends of the compressor members, and cross-over toggles connected to 40 the compressor members and to the sliding members, guides for the cross-over toggles, and plungers operatively related to the sliding members whereby the sliding members are actuated by the plungers after the plungers have moved to a predetermined extent.

20. In a device of the kind described, the combination of a pair of opposed parallel compressor members for one of the horizontal dimensions of a bale, another pair of opposed parallel compressor members pivoted and adapted to assume a vertical position 55 between the members of the first pair of compressor members, the members of the first pair having portions for interengagement with corresponding portions on the members of the second pair of compressor members, and means for first bringing the pivoted compressor members to the vertical position and for thereafter drawing the members of the other pair of compressor members toward each other and into inter-

engaging relation with the pivoted compressor members, comprising a plunger, means connected to the plunger and bearing upon the pivoted compressor members to bring them to the vertical position, sliding members adapted to be actuated by the plunger after the pivoted compressor members have been brought to the vertical position, and connections between the sliding members and the first-named compressor members.

21. In a device of the kind described, the combination of a pair of opposed parallel compressor members for one of the horizontal dimensions of a bale, another pair of opposed parallel compressor members pivoted and adapted to assume a vertical position between the members of the first pair of compressor members, the members of the first pair having portions for interengagement with corresponding portions on the members of the second pair of compressor members, means for first bringing the pivoted compressor members to the vertical position and for thereafter drawing the members of the other pair of compressor members toward each other and into interengaging relation with the pivoted compressor members, comprising a plunger, means connected to the plunger and bearing upon the pivoted compressor members to bring them to the vertical position, sliding members adapted to be actuated by the plunger after the pivoted compressor members have been brought to the vertical position, and toggles 100 between the sliding members and the first-named compressor members.

22. In a device of the kind described, the combination of a pair of opposed parallel compressor members for one of the horizontal dimensions of a bale, another pair of opposed parallel compressor members pivoted and adapted to assume a vertical position between the members of the first pair of compressor members, the members of the first pair having portions for interengagement with corresponding portions on the members of the second pair of compressor members, means for first bringing the pivoted compressor members to the vertical position and for thereafter drawing the members of the other pair of compressor members toward each other and into interengaging relation with the pivoted compressor members, comprising a plunger, means connected to the plunger and bearing upon the pivoted compressor members to bring them to the vertical position, sliding members adapted to be actuated by the plunger after the pivoted compressor members have been brought to the vertical position, and cross-over toggles between the sliding members and the first-named compressor members.

23. In a device of the kind described, the combination of opposed compressor mem-

bers for one horizontal dimension of a bale, opposed compressor members for the other horizontal dimension of the bale, and opposed compressor members for the vertical dimension of the bale, and fluid-actuated means whereby the first-named compressor members are moved toward each other, whereby thereafter the second-named compressor members are moved toward each other, and whereby thereafter the vertical compressor members are moved one toward the other.

24. In a device of the kind described, the combination of three compressor members, one for each dimension of a bale, fluid pressure operated means for operating the compressor members in sequence, said means holding each compressor member in compressing position while the succeeding compressor member is advancing to compressing position.

25. In a device of the kind described, the combination of three compressor members, one for each dimension of a bale, fluid pressure operated means for operating the compressor members in sequence, said means holding each compressor member in compressing position while the succeeding compressor member is advancing to compressing position, said fluid pressure operated means including controls whereby the compression of one of the compressor members may be released while the compression of another compressor member is held.

26. In a device of the kind described, the combination of a pair of opposed compressor members, a sliding member between the compressor members for actuating them, links connected to the sliding member, a bar con-

nected to each link and to the compressor members respectively, and a member having two pairs of fingers, the pairs being spaced apart to provide a way for the sliding member, and the members of each pair accommodating between them one of the bars.

27. In a compress, the combination with a swinging and bodily movable side platen, of a bodily movable end platen, and fluid-operated means for moving said platens bodily.

28. In a compress, the combination with a pivotally and bodily movable side platen, and a bodily movable end platen, of a common fluid-operated means arranged to move the platens bodily in sequence.

29. In a compress, the combination with a pair of swinging and bodily movable side platens, and a pair of bodily movable end platens, of a pair of fluid operated rams, one for each end of the side platens, and connections between each ram and its corresponding ends of the side platens and its corresponding end platen, whereby said platens are moved bodily.

30. In a compress, the combination with a pair of swinging and bodily movable side platens, and a pair of bodily movable end platens, of a pair of fluid operated rams, one for each end of the side platens, and connections between each ram and its corresponding ends of the side platens and its corresponding end platen, whereby said platens are moved bodily in sequence.

In testimony whereof I affix my signature in presence of two witnesses.

CHARLES J. LUCE.
